By Myself *Atma*

UNITED STATES PATENT OFFICE.

LYMAN C. WOOD, OF WICHITA, KANSAS.

VEHICLE-SPRING.

SPECIFICATION forming part of Letters Patent No. 242,731, dated June 7, 1881.

Application filed March 18, 1881. (No model.)

To all whom it may concern:

Be it known that I, LYMAN C. WOOD, a citizen of the United States, residing at Wichita, in the county of Sedgwick and State of Kansas, have invented certain new and useful Improvements in Vehicle-Springs; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

15 Figure 1 is a side elevation, partly in section, with the wheels removed, of a vehicle with my improved spring applied thereto; and Fig. 2 is a detailed view of the spring.

This invention has relation to improvements 20 in vehicle-springs, its object being to permit of the equalizing of pressure upon the springs and the distribution of the bearing-points of the springs upon the vehicle-body; and it consists of compound springs the convexities of 25 which are supported in or connected by clips to the vehicle-body, while their inner ends are connected to and adapted to have motion upon spindles or bolts depending from the vehicle-body, and encircled below the body with 30 springs, substantially as hereinafter more fully set forth and claimed.

Referring to the accompanying drawings, A A indicate the individual springs of the compound springs, one being arranged upon 35 each side of the vehicle. Each spring A is semi-elliptical in form, with its convexity supported in a clip, a, suitably bolted thereto, and, in turn, connected to the vehicle-body by a plate, b, bolted to the clip and to the under 40 side of the body, as seen in Fig. 1. The springs A, arranged in pairs upon each side of the vehicle, the rear springs being connected, as shown, or in other suitable manner, to the rear or hind axle, while, in addition to their attachment directly to the vehicle-body, they

are also connected indirectly to the vehicle-body at their inner ends. The forward springs, likewise directly connected to the vehicle-body, as before described, are connected in similar manner as the rearsprings to the bolster of the 50 front axle, while their inner ends are also indirectly connected to the body.

The means of attachment for the inner ends of each pair of springs consists of a plate, c, linked, as at d, to the said ends of the springs, 55 and fitted to slide vertically upon a bolt or spindle, B, extending up through the vehicle-body, and seated, preferably, as shown in Fig. 1, in a bridge or arch, e. Coiled around the spindle or bolt B, below the body, is a spring, 60 B', not necessarily, however, a coiled spring, which acts downwardly upon the plate c to secure it yieldingly in position upon the bolt.

From the foregoing it will be noticed that as weight is put upon the springs they will be 65 permitted to bear, not only at their convexity, upon the body, but also upon the center of the body, and thus distribute their points of bearing and equalize the pressure upon the springs.

It is also readily seen that greater resiliency 70 is obtained, which promotes comfort and ease.

Having thus fully described my invention, I claim and desire to secure by Letters Patent—

1. The combination of the semi-elliptical 75 springs A, arranged to connect with the hind axle and forward-axle bolster, and vertical sliding plate C, and bolt or spindle B, and spring B'.

2. The combination of the arch-spring e, 80 springs A A, clips b b, plate c, and spindle B, substantially as shown, and for the purpose described.

In testimony whereof I affix my signature in presence of two witnesses.

LYMAN C. WOOD.
